Primary Examiner — Shanda C Hill

(57) **CLAIM**

The ornamental design for a bottle, as shown and described.

DESCRIPTION

FIG. 1 is a top, right, front perspective view of the first embodiment of a bottle showing our new design;
 FIG. 2 is a top, left, front perspective view thereof;
 FIG. 3 is a rear elevational view thereof, the front elevational view being a mirror image;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is a top, right, front perspective view of the second embodiment of the bottle;
 FIG. 9 is a top, left, front perspective view thereof;
 FIG. 10 is a rear elevational view thereof, the front elevational view being a mirror image;
 FIG. 11 is a left side elevational view thereof;
 FIG. 12 is a right side elevational view thereof;
 FIG. 13 is a top plan view thereof; and,
 FIG. 14 is a bottom plan view thereof.
 FIGS. 1 through 7 depict indeterminate length. The broken lines shown in the drawing disclosure are for illustrative purposes only and form no part of the claimed design.
 In a preferred embodiment the bottle is useful for containing and dispensing insect control and/or cleaning products.
